(57) CLAIM

The ornamental design for a car air freshener vent clip, as shown and described.

DESCRIPTION

FIG. 1 is a front perspective view of a car air freshener vent clip showing my new design;

FIG. 2 is a back perspective view thereof;

FIG. 3 is a front view thereof;

FIG. 4 is a back view thereof;

FIG. 5 is a left view thereof;

FIG. 6 is a right view thereof;

FIG. 7 is a top view thereof; and,

FIG. 8 is a bottom view thereof.

The broken line is for the purpose of illustrating portions of the car air freshener vent clip and forms no part of the claimed design.
